FREDERICK P. SPRAGUE, OF WYANDOTTE, MICHIGAN, AND ONE-THIRD TO HARRY
G. MORRISON, OF TRENTON, MICHIGAN.

SAFETY DEVICE FOR PRESSES.

1,399,049.

Specification of Letters Patent. Patented Dec. 6, 1921.

Application filed October 30, 1919. Serial No. 334,560.

To all whom it may concern:

Be it known that I, HUDSON A. DAVENPORT, a citizen of the United States of America, residing at Wyandotte, in the county of Wayne and State of Michigan, have invented certain new and useful Improvements in Safety Devices for Presses, of which the following is a specification, reference being had therein to the accompanying drawings.

In the operation of punch presses and other machines having reciprocable rams, plungers and similar members, and more particularly those machines constructed for repeat operations, there is always danger of the operator or attendant of the machine having his hands under the ram or reciprocable member and a great many accidents have been caused by negligence or carelessness in connection with such machines.

The primary object of my invention is to provide a punch press or similar machine with positive and reliable means, in a manner as hereinafter set forth, for blocking or chucking a press or similar machine so that the ram or reciprocable member thereof cannot reciprocate unless the operator or attendant of the machine is prepared for such operation.

Another object of my invention is to furnish a punch press or similar machine with a novel chuck block which is operated in synchronism with the lever of the punch press and automatically released so that the chuck block will at all times be in position to prevent a repeat operation of the punch press, and thus eliminate such accidents as an operator or attendant having the hands or parts of the body injured by dies or the actuated parts of the punch press.

A still further object of my invention is to provide a safety device that may be easily and quickly installed in connection with ordinary punch presses, the device being simple in construction, durable and highly efficient for the purposes for which it is intended.

The above and other objects are attained by a mechanical construction which will be hereinafter specifically described and then claimed, and reference will now be had to the drawing, wherein—

Figure 1 is a side elevation of the safety

device as applied to a portion of a punch press;

55

Fig. 2 is a plan of the safety device, showing a portion of the punch press in section, and

Fig. 3 is a side elevation of a portion of the safety device illustrating an automatic release in connection with the same.

In the drawing there is illustrated a conventional form of punch press as including a base 1, a bed 2, a frame 3, and a reciprocable ram or member 4. It is between the bed 2 and the ram 4 that dies or any other members may be placed so that the various kinds of work can be performed by pressure. This type of machine is capable of having its ram repeatedly reciprocated and the operation of the ram is ordinarily controlled by a reach rod 5 and a trip lever or pedal 6, the latter being pivotally connected to the base 1 so that the operator or attendant of the machine can control the operation of the machine by foot pressure, thus leaving the hands free to manipulate a piece of work beneath the ram 4.

Suitably attached to the rear side of the base 1 is a bracket 7 and mounted on the bracket 7 is a housing 8 having parallel side walls 9. Connecting the lower portions of the side walls 9 are pivot pins 10 for arms 11 and 12, said arms having the upper ends thereof pivotally mounted by transverse pins 13 in slots or bifurcations 14 of a shiftable block holder 15, said block holder being disposed in a horizontal plane between the upper edges of the housing walls 9. The outer end of the block holder 15 is bifurcated or slotted, as at 16 to receive a vertically disposed chuck block 17 and said block is detachably clamped in the block holder so that it may be removed and blocks of different sizes placed therein, thus permitting of the safety device being used in connection with machines having variable ram strokes.

The arm 11 is of greater length than the arm 12 and the arm 11 has a slot 18 in its upper end through which extends the block pin 13, said pin being engaged by a coiled compression spring 19 within the slot. The expansive force of the spring 10 holds the pin 13 normally in the lower end of the slot 18, but when the block 17 is struck by the

ram 4 and the outer end of the holder 15 is tilted, then the inner end of the holder may swing upwardly with the pin 13 of the arm 12 serving as a pivot for the holder, thus 5 releasing the arm 11 of stresses and strains due to the block 17 being struck by the ram 4 should the same attempt to descend by a repeat operation.

The block holder 15 is provided with a 10 transverse keeper 20 and normally engaging said keeper are the hook shaped ends of latches 21 and 22, the former being in locked engagement with the keeper and the latter resting against the keeper to assume 15 a locked position when the keeper is shifted. The latch 22 is pivotally supported, as at 23, from one of the side walls 9 of the housing 8, and the latch 21 is pivotally connected to an arm 24 on a transverse bearing 20 pin 25, carried by the housing walls 9. The lower end of the fulcrumed arm 24 extends below the housing 8 and through the bracket 7 for connection with a link 26 which is connected to a crank 27 on the pivoted end of 25 the trip lever or pedal 6, and in consequence of the latch 21 being in positive engagement with the keeper 20, the block holder 15 will be retracted when the trip lever 6 is actuated. Such an operation will withdraw 30 the chuck block 17 from below the ram 4 and permit the ram to descend, providing the trip lever 6 is fully actuated, otherwise a coiled retractile spring 28 below the block holder 15, retains the block 17 beneath the 35 ram 4. The spring 28 is connected to a depending lug 29 of the holder 15 and to a transverse rod 30 connecting the housing walls 9.

When the block holder 15 is retracted the 40 latch 22 is raised to pass through the keeper 20 and lock the keeper in a retracted position, but the latches 22 and 21 are adapted to be raised to release the keeper 20 by the crank portion 34 of a ram operated arm 32 45 pivotally connected to one of the housing walls 9, as at 33, this ram lever having its outer end curved beneath the ram 4 and normally held in engagement therewith by a coiled retractile spring 31 connecting the 50 inner end of the lever to one of the housing walls 9.

In operation, pressure on the trip lever 6 will place the punch press in operation so that the ram 4 may descend, and simultaneously with the depression of the trip lever 6 55 the keeper 20 of the block holder 15 is retracted, causing the block holder to remove its block 17 from beneath the ram 4, so that said ram may descend and result in an operation being performed by the machine. As pointed out before, the latch 22 will momentarily engage the keeper 20 and hold the keeper so that the ram 4 can descend before the block 17 has a chance to interfere with its operation, but after the ram 4

reaches a predetermined position the lever 32 is actuated by the ram and raises the latches 21 and 22, so that the holder 15 will be released and the retractile force of the spring 28 may shift the holder 15 so that 70 the block 17 thereof will abut the side of the ram 4, as shown in Fig. 3. The block 17 will remain in such position until the ram 14 is raised sufficiently to provide clearance for the block 17 when said block is shifted 75 beneath the ram and prevents a repeat operation of the punch press.

Where the ram 4 has a short stroke the latch 22 will temporarily hold the block 17 so that the block cannot return before the 80 ram 4 is in position to prevent complete return movement, and it may be found that in connection with other types of presses it will be unnecessary to use the latch 22 and its operating mechanism. 85

It is thought that the operation and utility of my safety device will be apparent without further description, and while in the drawing there is illustrated a preferred embodiment of the same, it is to be understood that the structural elements are susceptible to such variations and modifications as fall within the scope of the appended claims. 90

What I claim is:— 95

1. The combination with a machine having a reciprocable member, and a lever for controlling the operation of said member, of a housing, a holder bodily movable in said housing and to and from said machine 100 and tilttable in a vertical plane relative to the machine, a block carried by said holder and normally in the path of said member, a latch normally engaging said holder, means supported from said housing connecting said 105 latch to said lever so that said latch may be operated to retract said holder when said lever is depressed, and means parallel to said latch and supported from said housing adapted to temporarily hold said holder 110 until said member is in the path of said block.

2. Means adapted to prevent a repeat operation of a press having a reciprocable ram, comprising a block normally in the path of 115 said ram and adapted to be retracted and so held by engaging the side of the ram, supporting means for said block permitting of said block self seating when struck by the ram to relieve said supporting means of 120 strains incident to the blow by the ram, and means operated by placing the press in operation to retract said block.

3. Means adapted to prevent a repeat operation of a press having a reciprocable ram, 125 comprising a housing for attachment to a press, a block normally in the path of the ram and yieldably supported from within said housing, means in said housing for shifting said block longitudinally thereof, 130

and means operated by placing the press in operation to actuate the means within said housing.

4. Means adapted to prevent a repeat operation of a press having a reciprocable ram, comprising a housing for attachment to a press, substantially parallel arms pivoted in said housing, a holder pivotally supported by one of said arms and loosely held by the other of said arms and extending 10 into the path of said ram, latch mechanism

adapted to retract said holder, latch mechanism adapted to temporarily hold said holder retracted, and means supported independent of said ram actuated by the ram 15 to release said latch mechanisms.

In testimony whereof I affix my signature in the presence of two witnesses.

HUDSON A. DAVENPORT.
